REEL HUB

Charles E. Gardner, Hollis, N.Y., assignor to Potter
Instrument Company, Inc., Plainview, N.Y., a corpo-
ration of New York

Filed Nov. 12, 1963, Ser. No. 77,382

Term of patent 14 years

(Cl. D61—1)

The figure is a perspective view of a reel hub showing my new design. The rear of the reel hub, not shown, is plain and unornamented. Also, the portion of the hub not visible when the handle is in the position depicted and the rear of the flip-down handle are plain and unornamented.

The fragmentary, broken-line showing of a reel is for illustrative purposes only.

I claim:

The ornamental design for a reel hub, as shown and described.
